UNITED STATES PATENT OFFICE.

LEVI S. GARDNER, OF SHREVEPORT, LOUISIANA.

INTERNAL-COMBUSTION ENGINE.

1,095,102.

Specification of Letters Patent. Patented Apr. 28, 1914.

Application filed June 10, 1912. Serial No. 702,655.

To all whom it may concern:

Be it known that I, LEVI S. GARDNER, a citizen of the United States, residing at Shreveport, parish of Caddo, State of Louisiana, have invented a certain new and useful Improvement in Internal-Combustion Engines, and declare the following to be a full, clear, and exact description of the same, such as will enable others skilled in the art 10 to which it pertains to make and use the same, reference being had to the accompanying drawings, which form a part of this specification.

In the ordinary internal combustion engine, in which the charge is fired by means of an electric spark it is impossible to obtain a low speed together with efficient operation, because either the combustible mixture is so dilute as to interfere with the 20 proper propagation of a flame or else the mixture must be made so rich as to result in a heavy deposit of free carbon. Even where it is attempted to obtain a low speed with a rich combustible mixture, the ignition will be uncertain unless the spark is 25 very powerful, and even then there is a loss of efficiency on account of the excess of combustible material and the losses arising on account of the carbon deposit.

The object of my invention is to provide 30 means whereby perfect ignition and combustion may be obtained at speeds much lower than have heretofore been practicable, without loss of efficiency.

In carrying out my invention I make use 35 of means for supplying a small charge of the proper combustible mixture at and maintaining it at the point where the ignition takes place. This may conveniently be accomplished by having the inner end of the 40 spark plug arranged within a small pocket which opens into the combustion chamber and which receives a small charge of combustible independently of the main charge 45 delivered to the cylinder. By filling this small pocket with combustible on the suction stroke of the engine, it remains within and is compressed within the pocket during the compression stroke and prevents the 50 pocket from being filled with the more dilute mixture in the combustion chamber proper. Consequently the pocket contains at the proper time a compressed charge of combustible of just the desired degree of 55 richness and the entire charge in the engine cylinder or combustion chamber may read-

ily be ignited through the ignition of the small charge contained within the pocket. The pocket may be filled in any suitable way, but I prefer to connect it to the main carbureter by means of a small pipe containing a check valve to prevent back flow; so that whenever the engine is drawing in a charge through the carbureter, it draws in an auxiliary charge into the pocket. I 60 prefer to connect the pipe leading to the pocket to the carbureter at a point back of the throttle valve so that the operation of the throttle valve to control the main charge 65 will have no influence on the auxiliary 70 charge.

The various features of novelty whereby my invention is characterized will herein-after be pointed out with particularity in the claim; but, for a full understanding of 75 my invention and of its object and advantages, reference may be had to the following detailed description taken in connection with the accompanying drawing, wherein:

Figure 1 is an elevation of a fragment of 80 an engine equipped in accordance with a preferred embodiment of my invention; and Fig. 2 is a vertical section an an enlarged scale through the device which carries the spark plug and contains the pocket adapted 85 to hold the auxiliary charge, an adjacent portion of the engine cylinder being also shown.

Referring to the drawing, 1 represents an engine having the usual inlet and exhaust 90 valves 2 and 3; the inlet valve being adapted to control the inflow of the main combustible charge through a pipe 4 leading from a suitable carbureter 5. In the particular arrangement illustrated, I have made provision for adapting my invention to engines 95 of any type which have already been built and are in use and, for the sake of brevity, I shall describe in detail only this particular form, although it will of course be 100 understood that the structural details may be widely varied without departing from my invention.

The engine which I have illustrated is one in which ignition is effected by means of 105 a suitable spark plug 6 and, instead of screwing this plug directly into the head of the cylinder or one of the walls of the combustion chamber, I screw it into the top of a member 7 which is in turn screw-threaded into the usual opening for receiving the spark plug as indicated at 8. The

member 7 is made hollow and is open at the top and at the bottom. The top is closed by means of a spark plug but the bottom remains open so as to place the interior of the member 7 in communication with the combustion chamber in the engine. The member 7 is made long enough so that the chamber within the same below the spark plug forms a pocket of considerable length. A pipe 9 leads from the carbureter to the member 7 and communicates with the interior thereof at a point just below the spark plug. The pipe 9 preferably joins the carbureter back of the throttle valve 10. The connection between the member 7 and the pipe 9 may take any suitable or convenient form, there being in the arrangement shown a nipple 11 on one side of the member 7 and the pipe 9 being fastened to the nipple by a suitable coupling 12. The inner end of the nipple communicates with the pocket or chamber within the member 7 through a radial passage 13. A suitable check valve 14 within the nipple permits fluids to flow from the pipe 9 into the pocket or chamber within the member 7, but prevents a back-flow.

The operation is as follows: When the engine is running, one charge after another is drawn in through the main inlet pipe 4 in the usual way. Simultaneously with the main charges, small auxiliary charges are drawn through the pipe 9 into the pocket 15 within the member 7. By making the inlet into this pocket radial, the incoming auxiliary charge does not flow out of the pocket immediately and enter the combustion chamber, but remains within the pocket. Consequently at the beginning of the compression stroke the pocket is full of a combustible mixture having a degree of richness determined by the adjustment of the carbureter and not influenced in any way by the character of the mixture in the main combustion chamber and cylinder. Therefore on the compression stroke of the engine, the charge in the pocket, as well as the main charge, is compressed; but the charge

in the pocket is compressed into the closed end, the main charge only entering the mouth of the pocket and mixing very little with the auxiliary charge which is compressed in front of it. Then, when the spark is made, or ignition is effected in any other suitable way in the pocket, there is present a small charge of the most suitable mixture for securing perfect ignition; this charge will be ignited and a flame will be propagated out through the pocket and into the main charge within the combustion chamber. In this way good ignition will always be obtained and, when the main charge is a very weak one, as is the case where the engine is running slowly, ignition of the main charge may be effected where this would be impossible if the primary ignition had to take place within the main charge.

While I have illustrated and described with particularity only a single preferred form of my invention, I do not desire to be limited to the structural details thus illustrated and described; but intend to cover all forms and arrangements which fall within the terms employed in the definitions of my invention constituting the appended claim.

I claim:

In combination, an internal combustion engine having a small pocket communicating with the combustion chamber, a carbureter, a connection between the combustion chamber and the carbureter for supplying the engine with a combustible charge, and an auxiliary connection between the carbureter and said pocket, a throttle valve in said carbureter, and said auxiliary connection opening into the carbureter on the side of the throttle valve opposite that on which the engine is located.

In testimony whereof, I, sign this specification in the presence of two witnesses.

LEVI S. GARDNER.
